UNITED STATES PATENT OFFICE.

ELMER KEEBLER, OF CHICAGO, ILLINOIS, ASSIGNOR TO THE MECHANICAL MANUFACTURING COMPANY, OF CHICAGO, ILLINOIS, A CORPORATION OF ILLINOIS.

VISCERA-INSPECTION TABLE.

1,380,563.

Specification of Letters Patent.

Patented June 7, 1921.

Application filed July 7, 1919. Serial No. 309,102.

To all whom it may concern:

Be it known that I, ELMER KEEBLER, a citizen of the United States, residing at Chicago, in the county of Cook and State of Illinois, have invented certain new and useful Improvements in Viscera-Inspection Tables, of which the following is a specification.

This invention relates to new and useful improvements in viscera inspection tables, and has for its object the provision of such a table the parts of which are readily cleansed.

In the present construction of viscera inspection tables the conveyer of the table is passed through a tank for the purpose of cleansing the flights of the conveyer. This is objectionable in that the fluid in the tank soon becomes filled with minute particles of the viscera and as the flights arise from the tank they cling to the surface thereof. In order to prevent this, I subject the flights of the conveyer to the action of jets of water and steam which force the particles from the flights and these particles are removed from the sterilizing chamber in which the cleansing operation takes place so that the flights in passing out of the sterilizing chamber do not come in contact with the particles.

Other objects and advantages of the invention will be apparent during the course of the following description.

In the accompanying drawings forming a part of this specification, and in which like numerals are employed to designate like parts throughout the same:

Figure 1 is a plan view of my device, a portion of the flights being broken away to show the arrangement of the sterilizing tank;

Fig. 2 is a section on line 2-2 of Fig. 1;

Fig. 3 is a side elevation of my device;

Fig. 4 is a longitudinal section through the sterilizing chamber;

Figs. 5 and 6 are perspective sections of the flights; and Fig. 7 is a perspective view of a link.

Referring now more particularly to the drawings, the numeral 10 indicates vertical standards connected by transverse supports 11 and an upper trackway support 12.

Secured to the upper trackway support 12 by means of brackets 13 are angle iron tracks 14 extending longitudinally of the

device. Similar tracks 15 are secured to the vertical standards 10 intermediate the support 11 and the trackway support 12 for a purpose hereinafter to appear.

At one end of the device is arranged a transverse shaft 16 driven from any suitable source of power. This shaft has mounted thereon sprocket wheels 17, the direction of rotation of the shaft being indicated by the arrow in Fig. 3. At the other end of the device is arranged an idler shaft 18 mounted in a longitudinally adjustable bearing 19 and provided with sprocket wheels 20.

Mounted for travel upon the sprocket wheels 17 and 20 is a conveyer 21 composed of sections 22 having an upstanding flange thereon and sections 24 similar to the sections 22 except that they are not provided with a vertical flange. The edge 25 of these sections or flights are machine finished for a purpose to hereinafter appear. Secured to the bottom of the flights by means of rivets or the like are link connections 26 provided at the connections with the rollers 27, the pivots at the juncture of the links being loosely mounted for a purpose hereinafter to appear. While I have shown the rollers as being spaced between each flange, it will be obvious that they may readily be more widely spaced without in any way interfering with the operation of the conveyer.

The flights are provided at their ends with supports 28 having mounted thereon rollers 29. It will be seen that the movement of the conveyer is supplied by the engagement of the teeth of the sprockets 17 with the rollers 27. Due to the direction of rotation of the sprockets the conveyer is pushed rather than pulled in its operative travel and the machine edges of the flights are forced into engagement affording a very tight joint. The rollers 27 on the upper receiving side of the flight rest upon the trackways 14 and in the return movement of the flights the rollers 29 rest upon the trackways 100

15. From the foregoing it will be seen that the flights themselves are not brought into contact with any surface which would produce friction. These flights being treated to the action of water are necessarily protected from the action thereof by galvanizing or the like and any frictional engagement will tend to remove the galvanizing and cause the flights to rust.

Arranged in the path of the returning 110

flights is a sterilizer casing 31. The flights enter at one end to an opening 32 formed in the casing. This casing is divided into three compartments A, B and C by transverse partitions 33 and 34. As clearly shown in Fig. 4, these partitions are provided with spring hinged doors 36 and 38. These doors are engaged by the vertical flanges 23 of the flights and open to permit the passage of the same.

The operation of my device is as follows:

As previously stated, the flights in their operative travel are pushed from the loading end of the table by sprockets 17 affording separate compartments for the viscera of each animal by reason of the vertical flanges 23 applied to some of the flights. The joints between the flights being tight little, if any, of the viscera leaks through to contact with the under mechanism of the conveyer. On their return movement, the flights enter the opening 32 and their receiving surfaces are subjected in compartment A of the sterilizer to the action of water supplied from a pipe 35. Passing through the compartment B, the flights are subjected to the action of steam on both receiving and under surfaces from pipes 37, undue escape of steam from the compartment being prevented by the spring doors 36 and 38. The action of the steam tends to loosen any particles not removed by the water in compartment A and these particles are removed when in compartment C where the receiving faces of the flights are again subjected to the action of water supplied from the pipe 39. The flights pass out of the conveyer through the opening 40 in the rear end thereof. As the flights are being pulled during the return movement the joints of the flights are slightly separated and accordingly are easily reached by the steam and water for cleansing. I have shown the bottom of the sterilizer as being inclined and provided in each of the compartments A, B and C with a drain for the purpose of carrying off the waste material and collected water.

It is to be understood that the form of my invention herewith shown and described is to be taken as the preferred example of the same, and that various changes in the shape, size and arrangement of parts may be resorted to without departing from the spirit of the invention or the scope of the subjoined claims.

Having thus described my invention, I claim:

1. In a device of the character described, an endless conveyer comprising a plurality of loosely connected flights, means for maintaining said flights in close engagement during the operative travel thereof, and means for separating the flights during their return travel.

2. In a device of the character described, an endless conveyer comprising a plurality of loosely connected flights, a pair of shafts on which said conveyer is mounted, drive means arranged on one shaft to push the flights of said conveyer during the operative travel and maintain them in close engagement with each other, and to separate the flights during their return travel.

3. In a device of the character described, an endless conveyer comprising a plurality of loosely connected flights, a pair of shafts on which said conveyer is mounted, drive means arranged on one of said shafts, a sprocket arranged on the drive shaft, said sprocket being adapted to engage the flights of the conveyer to drive it, said drive means being arranged to push the flights of the conveyer during their operative travel and maintain them in close engagement with each other, and to separate them during their return travel.

4. In a device of the character described, an endless conveyer comprising a plurality of flights, link connections secured to the flights, said link connections being provided with elongated openings whereby the flights may be loosely connected to each other, and means for pushing said conveyer during the operative travel whereby the flights are held in engagement with each other and spaced from each other during the return travel.

5. In a device of the character described, an endless conveyer comprising a plurality of loosely connected flights, means for maintaining said flights in close engagement during the operative travel thereof, means for separating the flights during their return travel, and means for sterilizing the flights of the conveyer during their return travel.

6. In a device of the character described, an endless conveyer comprising a plurality of loosely connected flights, means for maintaining said flights in close engagement during the operative travel thereof, means for separating the flights during their return travel, and means for subjecting said flights to jets of fluid during their return travel.

7. In a device of the type described, the combination with a conveyer embodying flights having machined edges, some of said flights being provided with an upstanding flange, links secured to said flights, pivots loosely connecting said links, means for pushing the flights during their operative travel and pulling the flights in their return travel whereby the machined edges of said flights are brought into close engagement during their operative travel and are slightly separated during their return travel, and means for supporting said flights in their return travel comprising longitudinal tracks and brackets secured to said flights having rollers thereon adapted to engage said tracks and support said flights, of means

- disposed in the path of travel of the returning flights for cleansing said flights comprising a casing through which said tracks extend, means mounted within the casing 5 for subjecting the flights to the action of water and steam, and yielding means extending into the path of the flanges on said flights adapted to obstruct the escape of steam from said casing.
- 10 8. In a device of the type described, the combination with a conveyer belt embodying flights having upstanding flanges thereon, of means for cleansing said flights comprising a casing disposed in the path of travel 15 of the returning flights, transverse partitions in said casing dividing the interior of said casing into compartments, openings formed in said casing and said partitions permitting the passage of the flights, spring 20 hinged doors partially closing the openings in said partitions and extending into the path of the flanges on said flights, means within said casing intermediate said partitions for subjecting said flights to the action 25 of steam upon their receiving and under faces, and means within said casing for subjecting said flights to the action of water before and after the action of the steam thereon.
- 0 9. The combination with an endless conveyer composed of loosely connected flights, and means for pushing the flights during their operative travel and pulling the flights during their return travel, whereby said 5 flights have their coacting edges in close en-
- gagement during such operative travel and separated during the return travel, of means for subjecting said flights to the action of water and steam during such return travel.
10. The method of cleansing flight conveyers consisting in positively separating the flights of the conveyer during a portion of the travel thereof and subjecting the flights while so separated to the action of a cleansing fluid. 40
11. The method of cleansing flight conveyers consisting in positively separating the flights of the conveyer during a portion of the travel thereof and subjecting the flights while so separated to the action of jets of 45 cleansing fluid.
12. The method of cleansing flight conveyers consisting in positively separating the flights of the conveyer during a portion of the travel thereof and subjecting the flights while so separated to the action of jets of 50 water and steam.
13. The method of cleansing flight conveyers consisting in positively separating the flights of the conveyer during the return 55 travel thereof and subjecting the flights while so separated to the action of jets of cleansing fluid so directed as to act upon the edges as well as the faces of the flights.
- In testimony whereof I affix my signature 60 in presence of two witnesses.
- ELMER KEEBLER.
